LATCHING MEANS FOR DIPPER DOORS

Paul V. Larsen, Oakland, Calif., assignor to Pettibone Muliken Corporation, a corporation of Illinois

Application June 25, 1942, Serial No. 448,513

5 Claims. (Cl. 293—188)

This invention relates in general to a latching mechanism for steam shovel dipper doors, and more particularly, to an improved adjustable latching mechanism.

A principal object of this invention is to provide a ruggedly constructed latching mechanism for power shovel dipper doors which will permit a high degree adjustment in order to compensate for the wearing of the dipper door latch bar.

Another important object of this invention is the provision of a latching mechanism for power shovel dipper doors, the working parts of which are secured in their proper relative positions by means of non-threaded elements.

A further object of this invention is the provision of a latching mechanism for power shovel dipper doors mounted in such a manner as to permit either right or left hand operation.

A still further object of this invention is the provision of a novel type clevis pin adapted to cooperate with and to secure the several moving elements of the latching mechanism.

Numerous other objects and advantages of the invention will become apparent as it is better understood from the following description, which, when taken in connection with the accompanying drawings, discloses a preferred embodiment thereof.

In the drawings:

Fig. 1 is an elevational view of power shovel dipper door embodying the features of this invention.

Fig. 2 is a cross-sectional view taken on lines 2—2 of Fig. 1.

Fig. 3 is a cross-sectional view taken on lines 3—3 of Fig. 1.

Fig. 4 is a cross-sectional view taken on lines 4—4 of Fig. 1.

Fig. 5 is a top elevational view of the latch lever.

Fig. 6 is a side elevational view of the latch lever.

Fig. 7 is a side elevational view of the latch bar guide.

Fig. 8 is a front elevational view of the latch bar guide.

Fig. 9 is a front plan view of the connecting link.

Fig. 10 is a side elevational view of the connecting link.

Fig. 11 is a perspective view of the interchangeable clevis bearing pin.

Referring now to the drawings, the reference numeral 2 indicates in general a power shovel dipper door. Hinge members 4 and 6 are rigidly

secured to the outer surface of the dipper door as by rivets 8, and are positioned adjacent the lateral edges of the door as is shown in Fig. 1. The door 2 is also provided with two horizontally extending cross members 10 and 12 which are rigidly secured to the outer surface of the dipper door by other rivets 8. The cross member 10 is mounted across the dipper door 2 intermediate its top and lower edges, while the cross member 12 is secured adjacent the lower edge.

Figs. 1, 7, and 8, illustrate in detail the construction of the cross member 10. As shown, the cross member 10 is substantially T-shaped in cross-section, and has integrally formed therewith the two transversely extending parallel walls 14 and 16 and a third wall 18 at right angles to the walls 14 and 16, thereby defining a substantially hollow rectangular passageway 19.

The cross member 12 is also provided with a similarly constructed rectangular passageway, detailed drawings of which are not shown in order to avoid duplication. The above described passages are adapted to receive slidably therein the latch bar 20. The latch bar is pivotally connected at its upper end to operating mechanism to be described in detail and the lower end of the bar is adapted to cooperate with locking mechanism (not shown) to secure the dipper door releasably in closed position.

Lugs 22 and 24 are integrally formed with the outwardly extending flange 26 of the cross member 10 and also with the transversely extending walls 14, 16, and 18. As illustrated in Figs. 1, 7, and 8, the lugs are disposed on opposite sides of the hollow rectangular passage 19. Lug 22 is provided with circular transverse openings 28 and 30, each of which is in coaxial alignment with apertures 32 and 34, respectively, formed in the cross member 10 (Figs. 7 and 8). In a like manner, the lug 24 is provided with apertures 36 and 38, each of which is coaxially aligned with corresponding apertures 40 and 42 formed in the cross member. Cotter key holes 44, 46, 48, and 50 are cored through the flange 26 and through the walls of the lugs 22 and 24. These openings intersect the openings 28, 30, 32, and 38. Raised shoulders 52 and 54 are provided on lugs 22 and 24, intermediate the apertures formed therein. Parallel and oppositely disposed bearing surfaces 56 and 58, 60 and 62 are also provided.

In Figures 1 and 3 I have illustrated a link member 64 pivotally and detachably secured between the bearing surfaces 60 and 62. Figures 9 and 10 disclose the details of the link construction. In these figures it will be noted that the

link is provided at one end with a single transversely extending opening 66, while the other end is somewhat enlarged and is provided with several spaced openings 68, 70, 72 and 74.

The link is detachably mounted between the bearing surfaces 60 and 62 by means of a clevis pin 76 which extends through the apertures 36, 66 and 40. The clevis pin is retained in position by a cotter key 78.

Figure 11 shows a perspective view of the clevis pin construction. This pin is provided with a round shank 80, one end of which terminates in a substantially rectangular flat head 82. A cotter key hole 84 is drilled through the shank at a point adjacent the head. The thickness of the head 82 and the height which the shoulders 52 and 54 extend beyond the outer side surfaces of the lugs 22 and 24 are approximately equal. Hence, it will be understood that when the pin is placed in position in the lug, the top surface of the pin will lie flush with the shoulder, thereby preventing serious damage to the head of the pin when it is brought into contact with the material being excavated. The head 82 is constructed so that a longitudinally extending edge lies adjacent the shoulder in order to prevent the pin from rotating.

The opposite surfaces 86 and 88 of the link 64 are designed to engage the opposed inner surfaces 90 and 92 of arms 94 and 96 of a bifurcated latch lever bar 98. As is seen in Figures 1, 3 and 4, one end of the latch lever bar is bifurcated, the arms of the bifurcation being provided with the transversely extending coaxially aligned holes 100, 102 and 104, 106 respectively. The apertures 109 and 104 have outwardly extending shoulders 108 of a length equal to the thickness of the clevis pin head 82, and cotter key passages 105 extending through the side walls of the arm 94 and intersecting the holes 100 and 104.

The link 64 is pivotally and detachably connected to the end of the latch lever bar by a clevis pin 76 which passes through the openings 104, 106 and any selected passage 68, 70, 72 or 74 of the link.

The upper end of the latch bar 20 is provided with an opening 109 (Figure 4). A clevis pin 76 is passed through the aligned openings 104, 106 and the opening 109 in order to secure the latch bar detachably and pivotally to the latch lever.

A latch lever guide member 110 is provided in order to limit the movement of the latch lever both in the direction of its normal movement and laterally thereof (Figures 1, 2 and 4). The guide member comprises a bar 112 having a longitudinally extending slot 114 adapted to receive slidably therein the handle portion of the latch lever 98. One end of the member 110 is provided with an offset flange 118. The other end has a projecting portion 116. Both the flange and the projecting portion have transversely extending openings such as those indicated at 120 and 122. The flange 116 is adapted to be releasably secured to the lug 22 by a clevis pin while the opposite end is affixed to the door 2 as by a bolt 123 and nut 125.

Operating means (not shown) are secured to the handle portion of the latch lever bar. As a latching mechanism is operated, certain wear occurs at the lower end of the latch bar 20. In the above mentioned mechanism I compensate for this wear by pivotally connecting the latch lever bar 98 to the link 64 successively through the spaced apertures 74, 72, 70, and 68. In con-

nected these transitions, the steps are as follows:

The latch lever bar 98 as shown in Figure 1 occupies the first position. In the second position the link 64 is disconnected from the aperture 36 formed in the cross bar 10 and is pivotally connected to the aperture 38, disposed laterally from the aperture 36 on the said cross bar. In position 3, the link 64 is disconnected from the aperture 38 and returned to the aperture 36 and the latch lever bar is disconnected from the aperture 74 and coupled to the aperture 72. In the fourth position the link 64 is disconnected from the aperture 36 and moved to and connected with the aperture 38.

In the fifth position of the latching mechanism the latch lever bar is connected with the aperture 70 and the link 64 is connected at its other end to the aperture 36. The sixth movement comprises the transition of the link 64 to the aperture 38. In position seven, the latch lever bar is connected to the aperture 68 of the link 64, the other end of the link 64 being pivotally connected to the aperture 36, and the final or eighth position comprises the transference of the pivotal connecting of the link 64 to the aperture 38.

In addition to the above advantages obtained by my latching mechanism, it will be noted that the working parts of my device may be reversed with respect to the latch bar 20 in order to permit either right or left hand operation.

The clevis pins used throughout my invention at each pivotal point are identical, thus permitting them to be interchanged. These pins are non-threaded, a factor which contributes to a long lasting and trouble free mechanism.

It will be apparent that while I have shown and described my invention in the preferred forms, many changes and modifications may be made in the structures disclosed without departing from the spirit of the invention, defined in the following claims.

I claim:

1. A dipper door latching mechanism comprising a cross member rigidly secured to one face of said dipper door, said cross member being provided with a centrally disposed passageway and a plurality of apertures disposed on opposite sides of said passageway at right angles thereto, a latch bar slidably mounted in said passageway, a latch lever bar, said latch lever bar being pivotally connected intermediate its ends to one end of said latch bar, a link member, one end of said link member being pivotally and selectively connected with one of said apertures, the other end of said link member being provided with a plurality of transversely extended openings, the center lines of said openings and said apertures being substantially parallel, and one end of said latch lever bar being selectively connected for pivotal movement to one of said openings.

2. A dipper door latching mechanism as defined in claim 1, and a latch lever guide, said latch lever guide having one of its ends releasably secured to said door, the other end of said latch lever being detachably secured in one of said apertures formed in said cross bar, said latch lever bar guide and said link member being disposed on opposite sides of said latch bar.

3. A dipper door latching mechanism comprising means for supporting a latch bar on one face of said dipper door for axial sliding movement into and out of latching position, a latch lever bar, said latch bar having one end pivotally con-

nected intermediate the ends of said latch lever bar, a link, means for pivoting said link to said door on either side of said latch bar, means pivotally connecting one end of said latch lever bar to the other end of said link selectively in any one of a plurality of positions, a latch lever bar guide detachably secured to said door, and means for detachably securing said latch lever bar guide to said door on either side of said latch bar.

4. In a latching mechanism for a dipper door, a latch bar supported on said door for axial sliding movement into and out of latching position, a latch lever bar having one of its ends bifurcated, said latch bar being pivotally secured between the arms of the bifurcated end portion and intermediate the ends of said latch lever bar, a link pivoted at one of its ends to said door, the other end of said link being pivotally connected

to said bifurcated end of said latch lever bar between said arms and, being selectively connected thereto in any one of a plurality of positions.

5. In the latching mechanism for a dipper door, a latch bar supported on said door for axial sliding movement into and out of latching position, a latch lever bar, said latch bar having one end pivotally connected intermediate the ends of said latch lever bar, a link, means pivotally and detachably connecting one end of said link to one end of said latch lever bar, selectively, in any one of a plurality of positions, and means for pivotally and detachably connecting the other end of said link to said door on either side of said latch bar, selectively, in any one of at least two positions.

PAUL V. LARSEN.
